GASOLINE COMPOSITION

Lawrence B. Scott, Lafayette, and Rupert C. Morris, Berkeley, Calif., assignors to Shell Development Company, New York, N. Y., a corporation of Delaware

No Drawing. Application November 14, 1955
Serial No. 546,798

9 Claims. (Cl. 44—72)

This invention relates to fuel compositions for internal combustion engines, especially gasoline, containing a certain class of organic boron compounds.

It is well known that certain combustion phenomena of spark-ignition internal combustion engines are advantageously affected by the presence of boron in the combustion chamber of the engine. For example, it has been found that gasoline containing minor amounts of boron in the form of soluble or dispersible boron compounds has an improved resistance to surface ignition and a decreased tendency to raise the octane requirement of the engine in which the gasoline is used. Among the compounds previously proposed for such purposes are the trialkyl borates and the trialkyl borines such as triisobutyl borate and triamyl borine, and more recently, certain classes of alkyl boronic acids and alkanediol esters thereof. Such compounds have been shown to be effective in these respects but their use has been limited to a varying extent by the relatively high solubility of such compounds in water, and also by the low resistance of such compounds to decomposition through hydrolysis. Such compounds are thus lost from gasoline, at least in part, by the "leaching" or hydrolyzing action of the free water with which the gasoline invariably comes in contact during commercial storage and handling. Another disadvantage of such compounds is that the only ones known to resist hydrolysis and leaching to any material extent contain only small amounts of boron in proportion to the rest of the molecule. Thus relatively large concentrations of such compounds are necessary to achieve a desired concentration of boron in the gasoline.

It is, accordingly, a principal object of this invention to provide an improved hydrocarbon fuel composition for internal combustion engines. A more particular object of the invention is to provide such a composition which has improved combustion characteristics. A further object of the invention is to provide a gasoline composition with improved resistance to surface ignition and less tendency to increase the octane requirement of the engine in which it is used. Still another object of the invention is to provide a boron-containing gasoline composition especially resistant to the action of water. Another object of the invention is to provide a gasoline composition especially resistant to the action of water and containing a boron additive the boron content of which is especially high. Another object of the invention is to provide a boron-containing gasoline composition the boron content of which can be especially high. Other objects will be apparent from the description of the invention.

It has now been discovered that these objects and others are attained by the addition to gasoline of a minor amount of certain heterocyclic boron compounds. The boron gasoline additives of the present invention are hexa-

2

tomic heterocyclic ring compounds or mixtures thereof with normal boiling points no higher than about 500° C. The heterocyclic ring of these compounds contains three boron atoms alternating with three nitrogen atoms. Each of the nitrogen atoms of the heterocyclic ring is attached directly to a carbon atom in an organic radical with a radical weight of at least 15, and each of the boron atoms of the heterocyclic ring is attached to a hydrogen atom, or to a carbon or nitrogen atom in a radical with a radical weight of at least 15.

The boron compounds of the gasoline compositions of the invention thus have the general formula:

wherein X is a hydrogen, or a radical with a radical weight of at least 15 and attached to the boron atom directly through an atom of an element having an atomic number of from 6 to 7 inclusive; and wherein Y is a radical with a radical weight of at least 15 and attached to the nitrogen atom directly through a carbon atom.

It is preferred that X be an organic radical and that the ring-connecting element of the X radical be carbon. It is also preferred that both X and Y be organic radicals and contain no more than 10 carbon atoms, and especially organic radicals containing no atoms other than carbon, hydrogen and nitrogen. Particularly suitable compounds are those in which X and Y are hydrocarbyl groups containing no more than 5 carbon atoms, and especially no more than 3 carbon atoms. Still better, especially in the case of Y, are such hydrocarbyl groups in which the atom attached to the ring is a secondary or tertiary carbon atom.

Because of the limitation of the maximum boiling point of the boron compound, and also so that the boron content of the compound be reasonably high, it is preferred that the total of the radical weights of the ring substituents be no greater than 500. Particularly advantageous compounds are those which have an especially high boron content, such as those in which the total of the radical weight of the ring substituents is no greater than 300, and preferably no greater than 250. On the other hand, in order that the gasoline compositions of the invention be especially resistant to the action of water, the total of the radical weights of the ring substituents of the heterocyclic boron compound should be at least 48, and preferably at least 125.

The heterocyclic boron compounds of the compositions of the invention are generally called "borazoles," the name borazole indicating the unsubstituted hexatomic ring compound $(BH-NH)_3$, and the substituents of the ring being named with "N—" and/or "B—" prefixes to designate their positions. Thus, for example, the compound with the structural formula illustrated above, wherein each X is a methyl group and each Y is an isopropyl group, is called "N-triisopropyl-B-trimethylborazole."

Among the borazoles suitable in the practice of the invention are: N-triphenyl-B-trimethylborazole, N-triphenyl-B-tris(dimethylamino)borazole, N-triphenyl-B-triethylborazole, N-tricyclohexyl-B-trimethylborazole, N-triisopropyl-B-trimethylborazole, N-triisopropyl-B-triethylborazole, N-triethyl-B-trimethylborazole, N-triisopropyl-

B-tris(dimethylamino)borazole, N-triisopropyl-B-triisopropylborazole, N-trimethyl-B-trimethylborazole, N-trimethyl-B-triaminoborazole, N-triisopropyl-B-tris(monomethylamino)borazole, N,N"-diisopropyl-N'"-methyl-B-trimethylborazole, N-triphenyl-B-triphenylborazole, N-tris(4-methylphenyl)-B-trimethylborazole, N-tribenyl-B-tris(B-aminoethyl)borazole, N-trimethyl-B-trianilinoborazole, N-triisopropyl-B-tripyrlylborazole, N-triisopropylborazole, N-trimethylborazole, N-triphenylborazole, N-tris(tertiarybutyl)-B-tris(4-tolyl)borazole, N-triisopropyl-B-tris-(isopropylamino)borazole, and the like.

The presence of lead or other metal-containing anti-detonants in a gasoline is well known to aggravate surface ignition and octane requirement increase, although these problems arise to some extent even with the so-called "clear" fuels, which do not contain anti-detonants. It has been found that the presence of boron in a gasoline is effective in decreasing the severity of these problems whether or not the gasoline also contains an anti-detonant, although the advantage is greater if the gasoline does contain an anti-detonant, especially a tetraalkyllead anti-detonant. Thus it is particularly advantageous to incorporate the present heterocyclic boron compounds into a gasoline containing an anti-detonant, especially a tetraalkyllead anti-detonant such as tetraethyllead.

The following examples illustrate the boron additives of the present invention, their preparation and the benefits and advantages thereof.

EXAMPLE 1

Preparation of N-tris(2-propyl)-B-trichloroborazole

N-tris(2-propyl)-B-trichloroborazole was prepared by reaction of isopropylamine with boron trichloride in the presence of triethylamine similar to a procedure used by Jones and Kinney [J. Am. Chem. Soc. 61, 1378 (1939)] for the preparation of N-triphenyl-B-trichloroborazole. This and other like compounds are especially suitable for the preparation of the additives of the invention as in the following examples.

EXAMPLE 2

Preparation of N-tris(2-propyl)-B-trimethylborazole

A reaction vessel was fitted with a ground glass stirrer, dropping funnel, condenser, and drying tube. Dry nitrogen was passed through the vessel for approximately 1/2 hour, and 310 grams (1 mole) of N-tris(2-propyl)-B-trichloroborazole (prepared as in Example 1) in 500 ml. of ether was added. To this solution at room temperature was added with stirring, over a period of 1 1/2 hours, methylmagnesium chloride (3.2 moles) in 3 liters of ether.

The mixture was stirred for 15 hours, filtered to remove the magnesium chloride, and the filtrate was added slowly to 1 liter of saturated ammonium chloride solution at 0° C., washed with water, and dried over anhydrous sodium sulfate. Evaporation of the ether followed by distillation of the product gave 224 grams (90.9% of the theoretical yield) of N-tris(2-propyl)-B-trimethylborazole, B. P. 101° C. (1 mm. Hg), M. P. 68-70° C. The material analyzed 58.0% carbon and 12.1% hydrogen as compared to a theoretical carbon and hydrogen content of 57.8 and 12.1%, respectively.

EXAMPLE 3

Preparation of N-tris(2-propyl)-B-tris(dimethylamino)borazole

A reaction vessel was equipped with a ground glass stirrer, condenser, dropping funnel, and a drying tube. Dry nitrogen was passed through the vessel for approximately 1/2 hour, and 310 grams (1.0 mole) of N-tris(2-propyl)-B-trichloroborazole in 2500 ml. of benzene was added. While the reaction mixture was kept at 30° C. with a water bath, a solution of 180 grams (4.0 moles)

of anhydrous dimethylamine and 404 grams (4.0 moles) of triethylamine in 1000 ml. of benzene was added over a period of 2 hours. The reaction mixture was stirred at room temperature for 15 hours, the triethylamine hydrochloride removed by suction filtration, and solvent was removed under reduced pressure on a hot water bath. The product was distilled to give 278 grams (83% of the theoretical yield) of N-tris(2-propyl)-B-tris(dimethylamino)borazole, B. P. 128-132° C. (1.6 mm. Hg). The material analyzed 54.3% carbon and 12.1% hydrogen as compared to a theoretical carbon and hydrogen content of 53.8 and 11.7%, respectively.

EXAMPLE 4

Preparation of N-tris(2-propyl)borazole

A reaction vessel was fitted with a stirrer, dropping funnel, condenser, and a drying tube. Dry nitrogen was allowed to flow through the vessel for 1/2 hour and then 58 grams (1.5 moles) of sodium borohydride and 177 grams (3 moles) of isopropylamine in 400 ml. of ether was added. To this mixture was added 34 grams (0.5 mole) of boron trifluoride etherate. After the reaction mixture had stirred for 15 hours, the ether was replaced with 500 ml. of toluene, and the reaction mixture was refluxed for an additional 15 hours. The precipitate was then removed by suction filtration, the solvent removed under reduced pressure, and the product distilled in a Claisen still. The product, a colorless liquid, B. P. 46° C. (1.1 mm. Hg), weighed 27 grams. The material analyzed 15.3% boron as against a theoretical boron content of 15.7% for N-tris(2-propyl)borazole.

EXAMPLE 5

In order to measure the advantages of the gasoline compositions of the present invention with respect to resistance to the action of water, each of the additives listed in Table 1 below was dissolved at the indicated concentration in a wet commercial gasoline, which though saturated with water at room temperature, contained no separate water phase. In the case of the water-unstable additives, a white precipitate was soon observed, indicating a decomposition of the boron compound with subsequent loss of insoluble decomposition product from the gasoline.

TABLE 1

	Compound	Concen- tration, percent w.	Observation
55	n-Butyl boronic anhydride ($C_4H_9BO_3$)	0.82	White precipitate on standing overnight.
	Tris(dimethylamino)borine	0.50	White precipitate on standing for 1 hour.
60	N-Trimethyl-B-triethyl borazole	0.66	No precipitate after 2 months.
	N-Triisopropyl-B-trimethyl borazole	0.35	No precipitate after 1 week.
	N-Triphenyl-B-trimethyl borazole	0.10	Do.
	N-Triphenyl-B-triethyl borazole	0.12	Do.

EXAMPLE 6

The following results also show the exceptional resistance to water of the gasoline compositions of the invention. Isooctane solutions of each of the compounds listed in Table 2 (at about 10% w. each) were shaken with an excess of distilled water in one series of tests, and each of these compounds in the pure, undiluted state was shaken with an excess of water in another series of tests. In the latter case, when there was no immediate change, the mixture was heated to about 90° C. on a steam bath.

TABLE 2

Compound	Isooctane Solution Shaken With Water	Compound Shaken With Water
Tricresyl borate.....	Immediate white precipitate.	Immediate white precipitate.
Triethyl borate.....	do.....	Immediate white precipitate plus evolution of heat.
N-tris(2-propyl)-B-trimethylborazole.	No change for at least 16 hours.	No change at 90° C. for at least 1 hour.
N-tris(2-propyl)borazole.	do.....	Do.
N-tris(2-propyl)-B-trichloroborazole.	Became cloudy immediately with evolution of heat.	Dissolved immediately with evolution of heat.
N-triphenyl-B-triethylborazole.	No change for at least 16 hours.	No change at 90° C. for at least 1 hour.
N-triphenyl-B-trimethylborazole.	do.....	Do.
N-triethyl-B-trimethylborazole.	do.....	Do.
N-tris(2-propyl)-B-tris(dimethylamino)borazole.	do.....	Slight precipitate after 16 hours at 90° C.

EXAMPLE 7

The benefits of the gasoline compositions of the invention with respect to octane requirement were shown in engine tests using a Lauson Model H-2 engine. This engine is a single-cylinder, spark-ignition, water-cooled engine with a 2 1/8 inch bore and a 2 3/4 inch stroke. It was modified for these tests by increasing its compression ratio sufficiently to adjust the clean-engine F-1 octane number requirement (with primary reference fuel) to about 65. The engine was thoroughly cleaned at the beginning of each test on a particular fuel, and operated during the test with a spark advance of 25° BTDC and on a cyclic schedule of 1 minute idling and 3 minutes cruise. The lubricant used was a common commercial crankcase oil. The octane requirement of the engine at full power output was determined at least once a day during each test.

A base gasoline consisting of a blend of toluene, iso-octane, and normal heptane containing sufficient "motor mix" fluid to supply 3.0 cc. tetraethyl lead per U. S. gallon was tested according to this procedure. The octane requirement of the engine leveled off after about 120 hours at 6±1 octane numbers above the octane requirement of the clean engine.

To the same base gasoline was added 1.8 grams of N-tris(2-propyl)-B-trimethylborazole per gallon (0.20 gram boron per U. S. gallon). When this fuel was tested according to the above procedure, the octane requirement of the engine leveled off after about 180 hours at only 1 to 2 octane numbers above the octane requirement of the clean engine.

EXAMPLE 8

The benefits of the gasoline compositions of the invention in suppressing preignition or "wild ping" were shown in the engine test designed to measure deposit-induced ignition which is described by Hirschler, McCullough, and Hall, "Deposit Induced Ignition Evaluation in Laboratory Engine," a paper presented at the Symposium on Preignition, Society of Automotive Engineers, Atlantic City, June 7-12, 1953. The engine used in this test is a CFR anti-knock test engine in which the standard overhead valve cylinder is replaced by L-head cylinder. The engine is operated on a cyclic schedule of 50 seconds of idling and 150 seconds at full throttle. The engine is equipped with an ionization gap and a surface-ignition counter. It thus differentiates between normal and uncontrolled combustion and counts the number of incidences of the latter.

By means of the above test, a commercial premium gasoline containing 3.0 cc. TEL/U. S. gallon, and this same gasoline also containing 1.8 grams per U. S. gallon of N-tris(2-propyl)-B-trimethylborazole per gallon (0.20 gram of boron per U. S. gallon) were compared for

tendency to cause preignition. The results were as follows:

TABLE 3.—INCIDENCE OF UNCONTROLLED COMBUSTION

5		Cumulative Counts	
		Base Gasoline	Base Plus 1.8 gm./gal. of Boron component
10	0 Hours.....	0	0
	20 Hours.....	1,400	350
	40 Hours.....	3,200	1,450
	60 Hours.....	5,200	2,500
	72 Hours.....	6,300	3,200
	0-72 hr. average, counts/hr.....	91	52
15	Final slope, counts/hr.....	95	74

EXAMPLE 9

The gasoline compositions of the invention are also improved with respect to oxidation stability measured by induction period and corrosivity. In these tests the base gasoline was a 58.5° API commercial premium automotive gasoline containing sufficient "motor mix" fluid to supply 3.0 cc. tetraethyl lead per U. S. gallon, 0.0003% w. of the commercial oxidation inhibitor, N,N'-disecondarybutyl-p-phenylene-diamine, and 0.00003% w. of the commercial metal deactivator, N,N'-disalicylal-1,2-propane-diamine.

This base gasoline has an induction period (average of two tests) of 9.9 hours by ASTM method D-525. The induction period of the same base gasoline containing 3.6 grams of N-tris(2-propyl)-B-trimethylborazole per U. S. gallon (0.4 gram boron per U. S. gallon) was 11.0 hours. The induction period of the same base gasoline containing 4.0 grams of N-tris(2-propyl)-B-tris(dimethylamino)borazole per U. S. gallon (0.4 gram boron per U. S. gallon) was over 22 hours.

For the corrosivity tests, the base gasoline, the base gasoline containing 3.6 grams N-tris(2-propyl)-B-trimethylborazole per gallon, and the base gasoline containing 4.0 grams N-tris(2-propyl)-B-tris(dimethylamino)borazole per gallon (compositions indicated below as "Base," "Gasoline A," and "Gasoline B," respectively) were each added to a separate phase of water and a sandblasted and isopentaneacetone washed drum steel strip was suspended into each gasoline sample so as to extend through the interface and into the water phase. The strips were observed and their appearance recorded periodically as follows, each system being maintained at normal room temperature:

TABLE 4

55	Appearance of Strip In—		
	Base	Gasoline A	Gasoline B
1 day.....	Slight rusting.....	No rust or discoloration.	No rust or discoloration.
10 days.....	Moderate rusting.....	Trace discoloration.	Do.
25 days.....	Heavy rusting.....	Slight rust.....	Do.

EXAMPLE 10

A gasoline containing from 0.005 to 1.0 gram of boron per U. S. gallon, in the form of N-tris(2-propyl)borazole, when tested according to the procedures of Examples 5, 6, 7, and 8, shows remarkable benefits with respect to resistance to the action of water, reduction of octane requirement increase and suppression of surface ignition.

EXAMPLE 11

A gasoline containing from 0.005 to 1.0 gram of boron, per U. S. gallon, in the form of N-trimethyl-B-trimethylborazole, when tested according to the procedures of Examples 5, 6, 7, and 8, shows remarkable benefits with respect to resistance to the action of water, reduction of

octane requirement increase and suppression of surface ignition.

Since, as already mentioned, the boron content of the heterocyclic boron compounds is very high, the effective concentrations of these compounds in the gasoline compositions can be very small. Generally, it is only necessary to include in the gasoline composition an amount of compound sufficient to supply a boron content of at least about 0.05 gram per U. S. gallon, and in many cases benefits are realized with as small an amount as 0.005 gram boron per U. S. gallon. On the other hand, it is desirable that the concentration of compound should not be greater than sufficient to supply a boron content of about 1.0 gram per U. S. gallon, or preferably, about 0.5 gram per U. S. gallon. A preferred concentration of compound is that sufficient to supply a boron content of from about 0.2 to about 0.4 gram per U. S. gallon.

Besides the heterocyclic boron additive, the gasoline compositions of the invention can, and ordinarily will, contain other additives, such as the common commercial additives, for example anti-detonants, such as tetraethyl lead, iron carbonyl, dicyclopentadienyl iron and derivatives thereof, xylidene and N-methylaniline, lead scavengers, such as ethylene dibromide and ethylene dichloride, dyes, spark plug antifoulers such as tricresyl phosphate, dimethyl xylol phosphate and diphenyl cresyl phosphate and diphenyl cresyl phosphate, other deposit modifiers such as other boron compounds and lower alkyl phosphates and phosphites, oxidation inhibitors such as N,N'-disubstituted - butyl - P - phenylenediamine, N - n-butyl-p-aminophenol and 2,6 - diteriarybutyl-4-methylphenol, metal deactivators such as N,N'-disalicylal-1,2-propanediamine, rust inhibitors such as polymerized linoleic acids and N,C-disubstituted imidazolines and the like.

We claim as our invention:

1. A gasoline composition consisting essentially of hydrocarbons boiling within the gasoline range and containing from about 0.005 to about 1.0 gram of boron, per U. S. gallon, in the form of a borazole compound boiling not higher than about 500° C. and having the formula:

wherein each X is selected from the group consisting of hydrogen and an organic radical having a radical atomic weight of at least 15 and attached to a ring boron atom through an atom of an element having an atomic number of from 6 to 7 inclusive, and wherein each Y is an organic radical having a radical atomic weight of at least 15 and attached to a ring nitrogen atom directly through a carbon atom.

2. A gasoline composition in accordance with claim 1,

wherein each Y is an organic radical containing from 1 to 10 carbon atoms.

3. A gasoline composition in accordance with claim 2, wherein each Y is a hydrocarbyl radical containing from 5 to 10 carbon atoms.

4. A gasoline composition in accordance with claim 3, wherein the borazole compound is N-tris (2-propyl) borazole.

5. A gasoline composition in accordance with claim 1, 10 wherein the amount of boron present in the form of the borazole compound is from about 0.05 to about 0.5 gram per U. S. gallon.

6. A gasoline composition consisting essentially of hydrocarbons boiling within the gasoline range and containing from about 0.005 to about 1.0 gram of boron, per U. S. gallon, in the form of a borazole compound boiling not higher than about 500° C. and having the formula:

wherein each X is an organic radical having a radical atomic weight of at least 15 and attached to a ring boron atom through an atom of an element having an atomic number from 6 to 7 inclusive, and wherein each Y is an organic radical having a radical atomic weight of at least 15 and attached to a ring nitrogen atom directly through a carbon atom.

7. A gasoline composition in accordance with claim 6, 35 wherein each X and each Y is a hydrocarbyl radical containing from 1 to 5 carbon atoms.

8. A gasoline composition in accordance with claim 6, wherein the borazole compound is N-tris(2-propyl)-B-tris(dimethylamino)borazole.

9. A gasoline composition in accordance with claim 7, 40 wherein the borazole compound is N-tris(2-propyl)-B-trimethylborazole.
